UNITED STATES PATENT OFFICE

2,638,674

DRAWING INSTRUMENT

Charles J. Worth, New York, N. Y.

Application June 4, 1948, Serial No. 31,037

10 Claims. (Cl. 33—77)

1

This invention generally relates to improvements in drawing instruments facilitating the making of perspective drawings.

Heretofore, the draftsman had to contend with large obstructions placed on the drawing platform for use with a perspective linead. Other types of perspective lineads are inaccurate as the pivotal point is usually placed off the working edge. With the perspective lineads in use today, it is impossible for a draftsman to remove his drawing from the drawing platform and then replace it and resume drawing without a great deal of resetting of his instrument and with all the resetting, the draftsman is rarely able to get complete accuracy.

The principal object of this invention is to aid the making of perspective drawings, and facilitate the removal and replacement of the drawing while not losing any accuracy.

Another object of this invention is to provide a device which will enhance the making of perspective drawings while the instrument is not unwieldy or difficult to use.

Another object is to provide a device whereby perspective drawings may be made more easily and accurately than has heretofore been possible.

Therefore, because of its novel construction, which will be described in detail, this device is unparalleled for accuracy and ease in using. It is small, light, compact and durable and can be used to pivotally join any size drawing instrument and drawing platform.

This device is neat in appearance, simple in design and possesses great utility in facilitating the making of perspective drawings.

Other objects and advantages will appear clear to those skilled in the art as the description proceeds and the novel features of construction, unique combination and the arrangement of parts will be more fully understood by referring to the accompanying drawings wherein:

Figure 1 is a plan view of a drawing board with three positions of a T-square incorporating the invention shown thereon.

Figure 2 is a partial plan view of a T-square incorporating part of the invention and a variation thereof mounted thereon.

Figure 3 is an end elevation of Figure 2.

Figure 4 is a cross-sectional elevation of the invention in a mated relationship.

Figure 5 is a cross-sectional elevation of the pivot.

Figure 6 is a plan view of Figure 5.

Figure 7 is a cross-sectional elevation of a modification of Figure 5.

Figure 8 is a cross-sectional elevation of a pivot base.

2

Figure 9 is a plan view of Figure 8.

Figure 10 is a plan view of a pivot base mount. Figure 11 is a cross-sectional elevation taken on line 11—11 of Figure 10.

5 Figure 12 is a cross-sectional side elevation taken on line 12—12 of Figure 11.

Figure 13 is an elevation of the modified pivot base.

In Figure 1, the conventional use of a T-square 10 22 on a working edge 20a of a drawing board 20 is shown at A the drawing board 20 having thereon a paper 21 which may have a perspective layout thereon. By the use of the invention, the T-square 22 may be pivoted at the right vision point (R. V. P.) on a pivot assembly 23 as is shown at B or at the left vision point (L. V. P.) as is shown at C on a similar pivot assembly 23.

As is shown in Figure 2, the T-square 22 may be composed of the conventional head 22a and a

20 T-square blade 22b joined together by screws 22c. Both the head 22a and the blade 22b are recessed to accept the pivot 40 or the modification 140 of the pivot assembly 23. The pivot 40 is held to the top of the T-square head 22a by screws 22d and has a top bearing surface 44a of the built-up portion 44 of the pivot 40 which is to be flush with the top surface of the T-square blade 22b. The pivot 140 is mounted to the bottom of the T-square head 22a by screws 22d and has a top bearing surface 144a of the built-up portion 144 which is to be flush with the top of the T-square blade 22b.

25 The centerpoint of the built-up portion 44 of the pivot 40 or 144 of the pivot 140 is on the same plane and is bisected by the working edge 30 of the T-square blade 22b. The accuracy of the

35 invention is directly dependent upon this assemblage. The more accurate the assembly is mounted, the more accurate the radiating lines will be. This pivot of the device will be more

40 fully described in detail in connection with the mating pivot base of the assembly; these parts being adapted to be mated to hold the T-square in proper position for use in drawing. It should be

45 understood that the T-square may be any type of a straight-edge while the drawing board may be any type of conventional drawing platform. The use of a T-square and drawing board is just the preferred form in the specification.

One form of the pivot base is shown at 30 in

50 Figures 4, 8 and 9 and comprises a downwardly extending tacklike point 31 and an upwardly extending center stud 32. The pivot base 30 also has a concentric cylindrical flange 34 extending upwardly from the base portion of the assembly

55 30 and separated from the stud 32 by a concentric groove 33 provided to accept the flange 43 of the pivot 40 or flange 143 of the modification

149 upon mating. These members of the pivot base 30 are to be concentric. To complete the pivot base 30, there is provided a flange 35 having a top bearing surface 35a.

The pivot 40 shown in Figures 4, 5 and 6 is comprised of a plate 41 having holes 41a for receiving the mounting screws 22d and a built-up portion 40a provided with a central hole 42 adapted to accept the stud 32 of the pivot base 30 or the stud 132 of the modification 130 upon mating of these assemblies and the pivot 40. The portion 40a has an inner concentric cylindrical flange 43 extending upwardly being accepted by the groove 33 of the pivot base 30 or groove 133 of the modification 130 upon mating of the assemblies. Outwardly of the flange 43 is a concentric cylindrical flange 44 separated from the inner flange by a concentric groove 45. This flange 44 surrounds the pivot base upon mating with the surface 44a riding on the bearing surface 35a of the flange 35.

When required, the pivot and pivot base may be varied in form as is shown in Figure 7 for the pivot and in Figures 10, 11, 12 and 13 for the pivot base.

A modified pivot 140 is adapted for attachment to the bottom surface of the T-square head 22a by the screws 22d extending through holes 141a in a plate 141 of the assembly. Because of the under surface attachment of the pivot 140, its built-up portion 140a is deeper than the portion 40a of the pivot 40. The portion 140a has a hole 142 adapted to accept the stud 32 of the pivot base 30 or the stud 132 of the modification 130, an inner concentric cylindrical flange 143 adapted to be received by the groove 33 of the pivot base 30 or groove 133 of the modification 130. There is an outer concentric cylindrical flange 144 which surrounds the pivot base when mated having a surface 144a which rides on the bearing surface 35a of the flange 35 of the pivot base 30. The flange 144 is separated from the inner flange 143 by a concentric groove 145 adapted to receive the flange 34 of the pivot base 30 or flange 134 of the modification 130 upon mating.

The variation of the pivot base, enabling a draftsman to place his vision points a measured distance beyond the periphery of the drawing board as is shown in Figures 10, 11, 12 and 13.

The pivot base 130, having an upwardly extending stud 132 is separated from the concentric cylindrical flange 134 by a concentric groove 133. In place of the tacklike point 31 in the pivot base 30, there is a downwardly extending threaded member 131 and a winged nut 131a used to hold and lock the pivot base 130 in place on the base mount 135. The base mount 135 has an arm 136 having a groove 136a to accept the pivot base 130, a slot 136b to accept the threaded member 131 and a second groove 136c to accept the winged nut 131a. The flange 136e formed around the slot 136b between grooves 136a and 136c becomes a track which is clamped between the pivot 130 and the winged nut 131a in locked position. The top face 136d of the arm 136 takes the place of the bearing surface 30a of the pivot base 30.

Extending laterally in the opposite direction of the arm 136, is the arm 137 having a downwardly extending tacklike member 137a and a small orifice 137b, both bisected by the extending centerline as is shown in Figure 10. Extending downwardly at the junction of the arms 136 and 137 is a section 135a having a face 135b. The face 135b is perpendicular to the centerline as is shown in Figure 10. At the base of member 135a is a

spring loaded arm 138 having a rounded outer edge 138a and forming a bifurcation with the arm 137. The spring tension of the arm 138 positively retains the tacklike member 137a in the drawing board while the face 135b is abutting the working edge 20a of the drawing board 20. It should be understood that all mating surfaces that have relative motion creating friction should be finished to give inherent self bearing characteristics to prevent binding.

Upon mounting the pivot base 30, all that is done is to put the tacklike point on the vision point and press into engagement with the drawing board 20. When mounting the pivot base 130, there is slightly more work required. The horizon line is plotted, upon which, the vision points are located by sliding the base mount 135 on the drawing board 20 until the face 135b abuts against the working face 20a. Align the base mount 135 until the horizon line bisects the orifice 137b, and the tacklike member 137a is placed on said line. Then, by pressing on the arm 137, engage the tacklike member 137a with the drawing board 20. The pivot base 130 can then be positioned on the arm 136 and locked in position with the winged nut 131a. Using this assembly, the vision point is definitely located when it is beyond the periphery of the drawing board.

Upon mounting the pivot 40 or the pivot modification 140 to the T-square or other similar instruments, the top bearing surface 44a of the pivot 40 or 144a of the pivot 140 is to be flush with the top of the blade, so no part is protruding beyond said surface. The centerpoint of the built-up portion 40a of pivot 40 or 140a of the modification 140 is to be on the same plane as the working edge of the blade and is to be bisected by it. The pivot base 30 or the modification 130 is placed on the left and right vision points. When the T-square is required to be used as a perspective lineand, it is turned face down so that the pivot and pivot base are mated, using the pivot at the uppermost working edge of the T-square according to the vision point at which it is to be used. All lines drawn on the top surface will radiate from the vision point being used. The bottom flange 35 of the pivot base 30 or the arm 136 of the base mount 135 will space the T-square head slightly from the drawing board and the paper while the bearing surfaces insure smooth and free swinging while the T-square is held positively in position. Thus, extra tools are eliminated, and the burdens of the draftsman are lessened.

The device functions also as a time-saving device, since no lining up or resetting is required as the tacklike point is always available as are the vision points. Also, the pivot base may be removed or the paper may be removed and be replaced without the danger of losing any of the accuracy of the drawing.

The invention eliminates the large bulky blocks that are now in use as well as keeping accuracy. It gives the draftsman more speed and relief from excess and unnecessary burdens and extra instruments. It helps advance and bring drafting up to date.

Although the invention has been described in detail, and with respect to certain preferred forms thereof, it is not desired to be limited thereto since changes and modifications which will become apparent to those skilled in the art may be made therein without departing from the

scope and spirit of the invention as more particularly set forth in the appended claims.

I claim:

1. In combination with a drawing instrument and a drawing platform, a pivot assembly having a pivot member attached to said drawing instrument having a built-up portion of a plurality of concentric recesses and projections capable of mating with pivot bases, said pivot bases capable of being positioned without the periphery of said drawing platform and detachably fixed thereto and retained by a downwardly extending piercing member.

2. In combination with a drawing instrument and a drawing platform, a plurality of pivot members fixedly attached to said drawing instrument and a plurality of pivot base members capable of mating with said pivot members, a pivot base mount portion of which part is positioned within the periphery of said drawing platform and the remaining portion of said pivot base mounting members positioned without the periphery of said drawing platform, said pivot base members being detachably mounted and retained thereto by a downwardly extending piercing member.

3. In combination with a drawing instrument and a drawing platform, a plurality of pivot members fixedly attached to said drawing instrument and a plurality of pivot base members capable of mating with said pivot members and detachably joined to and retained by a downwardly extending piercing member without the periphery of said drawing platform.

4. A pivot mounting assembly, capable of mating with pivots mounted upon a drawing instrument comprising a base portion capable of being positioned and locked on a slotted laterally extending arm, having a plurality of grooves and flanges, of a base mount which detachably mounts said base portion to a drawing platform, said base portion having complex means therein for the reception of the mating parts of a pivot portion secured to a drawing instrument above the drawing platform and being retained thereto by a downwardly extending piercing member.

5. An assembly for pivotally mounting a drawing instrument to a drawing platform with the pivot point positioned substantially beyond the limits of said drawing platform, comprising a pivot member, a base member and a base mount with a slotted laterally extending arm having a plurality of flanges and grooves; said pivot member attached to said drawing instrument and having a cylindrical built-up portion capable of mating with said base member, said base member capable of being positioned and locked on the arm of the base mount detachably mounting said pivot base to said drawing platform and being retained thereto by a downwardly extending piercing member.

6. An assembly for pivotally mounting a drawing instrument to a drawing platform, comprising a cylindrical pivot member, a pivot base member and a pivot base mount having a slotted laterally extending arm, said pivot member attached to said drawing instrument, said base member having therein a plurality of concentric annular portions forming channels for the reception of mating projections of said pivot member and said pivot base member capable of being secured to said drawing platform by said base mount and retained thereto by a downwardly extending piercing member.

7. In combination with a drawing platform and a drawing instrument, a pivot assembly compris-

ing a pivot member positively attached to said drawing instrument and having a built-up portion of a plurality of concentric annular rings capable of mating with and rotating on a base member which is positioned on a pivot base mount having a laterally extending slotted arm, said arm having a grooved portion about the slot in the upper and lower surfaces forming strengthening flanges on both sides of said arm, said groove in the upper surface of said arm being a housing for the lower portion of the pivot base and the groove in the lower surface being a housing for the pivot base locking nut, the top surface of said arm being an auxiliary bearing surface for the pivot member, said pivot base mounting portion being retained by the coaction of the spring loaded bifurcated arm and the piercing member.

8. In combination with a drawing platform and a drawing instrument, a pivot assembly comprising a first portion positively attached to said drawing instrument and having a built-up receiving section adaptable to mate with a second portion, said second portion being so constructed as to be capable of being positioned and locked on a laterally extending slotted arm of a third member, said third member detachably mounting the second member to the drawing platform and being retained thereto by a downwardly extending piercing member.

9. A T-square in combination with a drawing platform and a plurality of pivot assemblies comprising pivots attached to said T-square and substantially flush with the top surface of the blade thereof, pivot bases and pivot base mounts, said pivot base mounts having bifurcated portions and extending piercing members, which retain said base mounts to said drawing platform, and laterally extending slotted arms having a plurality of flanges and grooves upon which is positioned and locked said pivot bases, said pivot bases being capable of mating with said pivots.

10. A T-square, drawing platform and a pivot assembly capable of pivotally joining said T-square to said drawing platform enabling said T-square to operate normally and as a perspective line in its inverted position pivoting upon said pivot assembly, said pivot assembly comprising a pivot attached to said T-square substantially flush with the upper surface of the blade thereof, a pivot base and a pivot base mount, said pivot base mount having a bifurcated portion and an extending member cooperating together to retain said base mount to said drawing platform, said pivot base being positioned and locked upon a laterally extending slotted arm having a plurality of flanges and grooves of said pivot base mount and being capable of mating with said pivot.
